DESIGN FOR A GLOVE

Ross H. Higier, Johnstown, N. Y.

Application February 3, 1949, Serial No. 660

Term of patent 3½ years

(Cl. D3—11)

To all whom it may concern:

Be it known that I, Ross H. Higier, a citizen of the United States of America, residing in Johnstown, county of Fulton, and State of New York, have invented a new, original, and ornamental Design for a Glove, of which the following is a specification, reference being had to the accompanying drawing, forming part thereof, wherein

I claim:

The ornamental design for a glove, substantially as shown.

ROSS H. HIGIER.
